CLAIM

The ornamental design for a syringe aspiration ring, as shown and described.

DESCRIPTION

FIG. 1 is a perspective view of a syringe aspiration ring showing the claimed design;

FIG. 2 is top view thereof;

FIG. 3 is a side view thereof;

FIG. 4 is another side view thereof;

FIG. 5 is a front view thereof;

FIG. 6 is a back view thereof; and,

FIG. 7 is a perspective view showing the syringe aspiration ring of FIG. 1 with environmental structure.

The broken lines shown in FIG. 7 depict environmental structure that forms no part of the claimed design.
